UNITED STATES PATENT OFFICE.

PAUL HITZIGRATH, OF ROCKVILLE CENTER, NEW YORK.

HAIR CURLER.

Application filed November 18, 1924. Serial No. 750,549.

To all whom it may concern:

Be it known that I, PAUL HITZIGRATH, a citizen of the United States, and a resident of Rockville Center, county of Nassau, State of New York, have invented certain new and useful Improvements in Hair Curlers, of which the following is a specification.

This invention relates to hair curlers, a particular object of which is to provide means of simplified and improved construction whereby the hair may be easily applied to the device, the device may be quickly and easily manipulated to twist or curl the hair, and the device may be securely clamped or retained in proper position to hold the hair securely until the curling operation is complete.

A further object is to provide a device of this character and for these purposes featured by simplicity and cheapness of construction; which may be easily manufactured, which may be marketed at extremely low costs, and which will prove highly effective in operation.

With these objects in view, together with others which will appear as the description proceeds, the invention consists in the novel construction, combination and arrangement of parts, all as will be described more fully hereinafter, illustrated in the drawing, and particularly pointed out in the claims.

In the drawings;

Fig. 1 is a perspective view of a curler embodying the invention as it will appear before use,

Fig. 2 is a similar view, showing the parts in the positions they will assume when ready to be applied to the hair,

Fig. 3 is a view similar to Fig. 1, and illustrating a slight modification of the invention, and

Fig. 4 is a plan view of the modified form of curler, with a part of the binder or head removed.

Referring now to the drawing, and particularly to Figs. 1 and 2 thereof, the curler of the preferred form comprises a body consisting of spaced parallel outer strands 5 and 6 of pliable material. In the present form, these strands are of appropriate length, and may be formed of thin wire of a pliable or flexible nature, covered with fabric of any desired character to prevent injury to the hair and to obviate the occur-

rence of protuberances which might cause discomfort to the user as well as to offer opportunity for hair tangling. The outside strands 5—6 have arranged between them an intermediate strand of similar length, form 60 and construction, indicated at 7. These strands constitute the body of the curler, and their ends are bound together by tape or any other suitable tough material to provide heads indicated at 8. 65

It is preferred that the outer strands 5—6 be of similar color, while the intermediate strand 7 may be of different color so as to provide a perceptible contrast. In operating the curler, the outside strands 5 and 6 are 70 grasped by the fingers and bowed outwardly in opposite directions as indicated in Fig. 2. The central or intermediate strand 7 is pulled outwardly in a direction at substantially right angles to the path of movement 75 of the strands 5—6. When this has been done, a space has been provided between the strands 5—6 and the outwardly bowed intermediate strand 7 of sufficient size to enable a lock or bulk of hair to be inserted 80 between the strands thus extended. When this has been done the heads 8 are grasped in the hands and outward movement in a direction longitudinally of the body is given. This causes the bowed strands 5—6—7 to 85 move back to substantially normal position, so that the body of hair will be tightly confined and bound between the several strands of the body. With the hair thus held, the curler is rolled laterally so that 90 the bulk of hair winds itself upon the intermediate portion of the body, and when this operation is complete, the end portions of the body are bent inwardly toward and over the central portion of the body 95 and in tight engagement with the rolled hair. This manner of bending is indicated by dotted lines in Fig. 1, and it is apparent that with the hair thus tightly rolled and clamped, danger of unrolling or detachment 100 of the curler is obviated. It is preferred that the several strands constituting the body be of sufficient flexibility to permit of ready manipulation in the manner stated, yet will possess sufficient resistance qualities to prohibit casual unbending or detachment. When the hair thus curled has been allowed to remain a proper time, the curler may be detached by resorting to an operation just the reverse of that above detailed. 105

In Figs. 3 and 4 of the drawing there is illustrated a slight modification, wherein the outer strands 5—6 are formed of a single length of wire, bent into substantially 5 U-shape at a point intermediate its ends, and the intermediate strand 7, similar in all respects to the corresponding strand 7 in the preferred form, is interposed between the legs 5—6. The intermediate strand 7 10 has one end thereof, together with the free ends of strands 5—6, bound or taped to provide the head 8 as shown, and the opposite end of strand 7 may terminate inwardly from the bight portion of the outer 15 strand 7 to enable easy manipulation of the curler. In operating this form of curler, the strand 7 is moved outwardly in the manner indicated by dotted lines in Fig. 3, and, if desired, the strands 5—6 may be bowed 20 outwardly or they may remain substantially parallel. When the hair lock has been inserted at its end between the strands 5—6—7, the intermediate strand is moved back toward normal position, and the rolling process 25 is carried out, whereupon the ends of the body are flexed inwardly toward each other

to lock the device in proper position upon the rolled hair.

From the foregoing it is apparent that I have provided curling means for hair strands of extremely simple nature, which lends itself admirably either to long or bobbed hair, which is capable of being securely attached to the hair without danger of snarling or entangling the latter, and which will prove highly effective in carrying out hair curling process.

Having thus described my invention, I claim:

1. In a hair curler, a body comprising outer strands and an intermediate strand formed of pliable material, and heads securing the ends of said strands together. 40
2. In a hair curler, a pair of spaced parallel pliable strands, an intermediate strand disposed between and parallel with the outer strands, all of said strands being in close proximity to each other and all of equal length, and heads connecting the ends of said strands together. 45

In testimony whereof I affix my signature
PAUL HITZIGRATH. 50
